UNITED STATES PATENT OFFICE.

MORRIS E. STANTON, OF RICHMOND, INDIANA, ASSIGNOR TO F. & N. LAWN MOWER COMPANY, OF RICHMOND, INDIANA, A CORPORATION.

DESIGN FOR A LAWN-MOWER CASING.

No. 38,340.

Specification for Design.

Patented Dec. 4, 1906.

Application filed August 29, 1906. Serial No. 332,542. Term of patent 14 years.

To all whom it may concern:

Be it known that I, MORRIS E. STANTON, a citizen of the United States, residing in the city of Richmond, in the county of Wayne and State of Indiana, have invented a new, ornamental, and original Design for Lawn-Mower Casings, of which the following is an accurate specification.

In the accompanying drawings, forming a part of this specification, Figure 1 shows an outside elevation of one end of a lawn-mower casing containing my invention, and Fig. 2 shows an inside elevation of the same.

Said views when taken together show all of the essential features of this design, and it will of course be understood that the other side of the lawn-mower is a duplicate of the side shown and referred to.

I claim—

The ornamental design for a lawn-mower casing, as shown.

MORRIS E. STANTON.
